W. S. HAMM & A. H. NEWPHER.
WEATHER GUARD FOR WINDOWS.
APPLICATION FILED APR. 3, 1911.

1,029,188.

Patented June 11, 1912.

UNITED STATES PATENT OFFICE.

WILLIAM S. HAMM, OF HUBBARD WOODS, AND ALFRED H. NEWPHER, OF CHICAGO,
ILLINOIS, ASSIGNORS TO THE ADAMS & WESTLAKE COMPANY, OF CHICAGO, ILLINOIS,
A CORPORATION OF ILLINOIS.

WEATHER-GUARD FOR WINDOWS.

1,029,188.

Specification of Letters Patent. Patented June 11, 1912.

Application filed April 3, 1911. Serial No. 618,727.

To all whom it may concern:

Be it known that we, WILLIAM S. HAMM and ALFRED H. NEWPHER, citizens of the United States, and residents, respectively, 5 of Hubbard Woods, county of Cook, and State of Illinois, and Chicago, county of Cook, and State of Illinois, have invented certain new and useful Improvements in Weather-Guards for Windows, of which 10 the following is a specification, and which are illustrated in the accompanying drawings, forming a part thereof.

The invention relates to weather guards for windows, and is particularly adapted 15 for use on the side rails of a sliding sash; its object is to secure an air tight joint without material friction tending to retard the movement of the sash.

A further object is to provide a construction which will have great durability and be permanently reliable.

The invention is fully hereinafter described, and is illustrated in the accompanying drawings, in which—

25 Figure 1 is a detail perspective, partly in section and partly broken away, of a window casing and sash mounted therein; Fig. 2 is a longitudinal section of the guard; and Fig. 3 is a detail cross-section on the 30 line 3—3 of Fig. 2.

In the drawings the invention is shown in connection with a window especially adapted for car construction, and there is represented at 10 a portion of the outer wall 35 of a car body and consisting of a metal plate; at 11 is shown a window sill; at 12 one of the stiles of the window casing and having an adjustable stile plate 13 and sash stops or guides 14, 15 and 16; at 17, 18, are 40 shown a pair of sash fitted within the sash-ways bounded by the stops. While two sashes, an outer and an inner one, are shown, the invention is equally applicable to a single sash window.

45 An angle plate 19 is secured by means of screws, as 20, 21 and 22, to the outer face of the side of the car. As shown, the stile 12 is provided with a flange 23, which is folded back on the outer face of the wall plate 10; and 50 the outer leaf of the angle plate 19 is fitted directly upon this flange, its edge overlapping the same and being turned inward to meet the plate 10 for the purpose of forming a tight joint therewith. The instanding

leaf 24 of the plate 19 makes a loose contact with the outer sash 17, and is spaced apart from the outer stop 14, forming therewith a chamber having an open side directed toward the sash. Within the chamber thus formed there is housed a longitudinal 55 bar 25, to which is applied a pair of plates 26, 27, of elastic sheet metal, the former extending along the face of the bar adjacent the stile 12, and the latter extending along the opposite or outer face of the bar. The 60 plates 26, 27, project inwardly toward the sash, and their inner portions are inclined 65 toward each other, the free edge 28 of the plate 27 bearing against the inwardly folded portion of the plate 26 and the free edge 70 29 of the latter plate being adapted to bear against the outer face of the sash 17. To prevent wear the side rail of the sash, when of wood as shown, is preferably covered with metal, as at 30.

75 A spring, as 31, is applied to the back or outer face of the bar 25, and reacts against the outer wall of the plate 19 for the purpose of urging the bar and the plates carried thereby toward the sash. The plates 80 26, 27, may be formed of a single sheet folded about the bar 25, and may be conveniently secured thereto by means of screws, such as 32, of any desired number, one of which is shown, and as serving also to attach the 85 spring 31 to the bar. The spring 31 presses the bar 25 toward the sash with sufficient force to insure a slight flexure of the inwardly folded flange of the plate 26, thus causing it to make a tight joint with the 90 flange 28 of the plate 27, and a tight joint with the sash by the engagement therewith of its edge 29. We have found that by this construction drafts are completely excluded, even at extremely high wind pressure, and 95 the efficiency of the guard is materially increased by so disposing the spring plates that an edge of one of them bears obliquely against the sash and is presented to the weather.

100 We claim as our invention—

1. In a weather guard for windows, in combination, a stile having a longitudinal chambered casing, such chamber having an open side facing the sash-way, a floating bar 105 within the casing, a pair of flexible plates carried by the bar and folded to overlap, one of said plates having its free edge pre-

sented to the sash-way and adapted to engage a sash, and a spring urging the bar toward the sash-way.

2. In a weather guard for windows, in combination, a stile having a longitudinal chambered casing, such chamber having an open side facing the sash-way, a floating bar within the casing, two flexible plates of spring metal attached to the bar and projecting from opposite sides thereof toward the sash-way, such plates having their free

edges turned inwardly and overlapping, the edge of one of such plates being adapted to engage a sash, and the edge of the other engaging the inner face of the instanding portion of its companion, and a spring urging the bar toward the sash-way.
